UNITED STATES PATENT OFFICE

2,239,524

RECORDING APPARATUS

Harold Glenn Johnstone, Oak Park, and Norbert Karl Engst, Berwyn, Ill., assignors to Western Electric Company, Incorporated, New York, N.Y., a corporation of New York

Original application August 28, 1928, Serial No. 302,463. Divided and this application February 6, 1929, Serial No. 337,851

24 Claims. (Cl. 235—61.10)

This invention relates to recording apparatus, and more particularly to perforating apparatus for use in combination with computing devices.

This application is a division of our copending application Serial No. 302,463, filed August 28, 1928.

The primary object of this invention is the provision of a recording device which may be operated efficiently at high speed and which responds to prepare accurately a record on a sheet in accordance with information transmitted thereto.

Another object of the present invention is to provide a computing and recording mechanism for effecting mathematical computations and recording the result of said computations on record sheets.

In accordance with the above objects, the present invention contemplates a perforating apparatus especially adapted for recording information in statistical and like cards by perforating apertures in differently allocated areas or zones of the cards. This apparatus includes a key board having a plurality of groups of keys, which groups correspond to the several areas or zones of the statistical and like cards. These keys serve to control the closure of circuits extending to a switching mechanism comprising a plurality of stationary contacts and a brush individual to each set of contacts, which brushes serve to complete electrical circuits through the contacts corresponding to the particular keys which have been operated in the various groups and the associated mechanism to selecting electromagnets embodied in the perforating apparatus.

In one embodiment of the invention, certain groups of the keys are designated as multiplicand and multiplier keys, respectively, on which a given problem may be set up, the product of which is desired to be recorded in an allocated area or zone of the statistical card.

The selecting electromagnets are mounted in arcuate, staggered relation to permit the location of a plurality of such electromagnets in a relatively small area and are energized in accordance with the depression of the keys of the key board which may condition circuits directly to the switching mechanism and/or which may cause the operation of the multiplying mechanism to function in a manner to obtain the product of a designated multiplicand and multiplier. Individual to each of the selecting electromagnets is a selecting bar which is common to a plurality of perforating pins and which is adapted to be moved positively until it assumes a position in vertical alignment with a desired perforating pin which is deter-

mined by the time of operation of the selecting electromagnet. Specifically, the mechanism for effecting the movement of the selecting bars consists of a segmental gear which extends transversely of the selecting bars and which upon being rotated cooperates with a serrated portion of the selecting bars which are selected at different points in the rotation of the segmental gear through the operation of the selecting electromagnets and moved to positions in vertical alignment with the desired perforating pins.

Following the movement of the selecting bars in this manner, mechanical means is operated for causing the downward movement of a ram common to the perforating pins for positively moving the perforating pins selected in accordance with the movement of the selecting bars, thereby causing the numerals set up on the key board or the product resulting from the multiplication of the designated figures to be expressed in the card in the form of perforations or apertures.

In accordance with a specific embodiment of the invention, an unperforated card which is to receive the information in the form of perforations is advanced automatically to a position beneath the perforating pins, which advancement is in synchronism with the operation of the segmental gear which effects the movement of the selecting bars in accordance with their selection, as determined by the operation of the selecting electromagnets. Retraction of the perforated card is also effected automatically upon the restoration of the perforating ram and it is consequently discharged into a hopper designed to receive it.

In the preferred embodiment of the invention it is proposed to effect computations with a computing system using an electrical multiplying mechanism in which there are nine sets of nine each of electrical contact disks, each contact disk representing the product of one digit by another digit and provided with an associated contact brush so that the position of a contact on one-half of the circumference represents the unit number of the particular product and a contact on the other half the tens part. The multiplicand and multiplier are set up on the groups of keys allotted to them to effect the closure of electrical circuits; whereby beginning with units, power is fed, for each digit in the multiplier, one at a time, through the contacts on the disks through distributing brushes to an accumulating device which completes electrical circuits to the contacts of the switching mechanism of the perforator. The distributing brushes transfer the

electrical connections from units to tens, tens to hundreds, hundreds to ten-hundreds, etc., at the proper point in each cycle. The entire product of a digit in the multiplier by the multiplicand is accumulated on the accumulating device for one revolution of the contact disks. When the final product is set up in the accumulating device the perforator is operated to perforate a card in accordance with the result standing in the accumulator and the information set up on the key board.

The above and other features of the present invention will be fully set forth in the following description and appended claims, and will be more readily understood by reference to the accompanying drawings, wherein

Fig. 1 is a plan view of the apparatus embodying the features of this invention;

Fig. 2 is a rear elevation of the apparatus shown in Fig. 1;

Figs. 16 and 17 are sectional views taken on the lines 16—16 and 17—17, respectively, of Fig. 13 in the direction of the arrows showing one of the disk units on the multiplying commutator, and

Fig. 18 is an enlarged fragmentary schematic of three of the nine sets of nine each of the contact disks representing the electrical multiplication system on the multiplying commutator.

In the practical application of the present invention, the apparatus utilized for the accomplishment of the objects of the invention consists of three principal parts, a key board 5, a computing or multiplying mechanism 6, and a perforating or punching mechanism 7. Each of these just referred to parts of the apparatus embodying the features of this invention have been designated

generally by the respective numerals and will be described more in detail later.

Referring now to the key board which is shown in Fig. 1, a plurality of keys are arranged in various groups depending upon the character of the information desired in a statistical card of the character shown in Fig. 9, the keys making up the key board 5 are mounted in strips or rows in a manner similar to that described and disclosed in A. D. Hargan Patent No. 1,378,950, issued May 24, 1921. As disclosed in this Hargan patent, a member common to a plurality of keys is provided for maintaining the keys in an actuated condition once they are depressed. For the purpose of restoring the actuated keys to normal, an electromagnet 8 operatively connected to the member common to the keys has its operating winding connected with a suitable control circuit which, when closed, causes its energization and thereby the restoration of the depressed keys to normal. Inasmuch as the details of the key construction do not constitute a part of the present invention, a detailed description of the construction and operation of this part of the mechanism is believed to be unnecessary.

As previously mentioned, the key board 5 is divided into a plurality of groups of keys. Each of these groups of keys controls the operation of contacts indicated generally by the numeral 9 (Fig. 4) which contacts serve to control the closure of electrical circuits to be explained later.

Positioned at opposite sides of the key board 5 are two elongated members 15 and 16 which function to control various starting operations of the apparatus. For example, the member 15 through suitable contacts associated therewith, when depressed, causes the closure of circuits extending to mechanism for setting into operation the computing or multiplying mechanism referred to generally by the numeral 6 (Fig. 10). Likewise, the member 16 serves to control suitable contacts and consequently the closure of electrical circuits extending to apparatus for initiating the operation of the elements constituting the perforating mechanism indicated generally by the numeral 7.

In order that the keys in the various groups of keys may be selectively connected to various other circuits, control mechanism indicated generally by the numeral 10 is provided. This mechanism 50 consists of a plurality of jacks 11 (Fig. 1) designed to receive plugs 12 and 13 which are attached to opposite ends of a flexible cord 14. By means of the flexible cord 14 and the plugs 12 and 13 various combinations of circuits may be 55 established. The purpose and function of such flexible cords will be more fully described in the description pertaining to the operation of the apparatus.

The computing or multiplying apparatus which 60 has been designated generally by the numeral 6 comprises mechanism controlled by the depression of keys in the respective groups of keys set apart for the multiplicand and multiplier for computing the desired problem.

The perforating mechanism comprises a plurality of electromagnets 25 arranged in an arculate staggered relation to permit the location of a large number of such electromagnets in a relatively small area. Each of these magnets is provided with suitable armatures 26 shown more clearly in Figs. 2 and 3 as being operatively associated with pivoted, bell crank levers 27. According to the preferred embodiment of the invention, the electromagnets 25 are mounted on rectangular shaped members which are secured

to side plates 21 and 22 on the arc of a circle and are arranged in a manner such as to permit the ready, easy and quick removal of an electromagnet without disturbing any of the other electromagnets. The axis of the arc on which the rectangular shaped members supporting the electromagnets are mounted corresponds approximately with the pivotal point of the bell crank levers 27. These bell crank levers 27 are pivoted to a rod 28 and are moved from their normal position against the action of a spring 29 individual to each bell crank lever. When the electromagnet is deenergized the spring 29 is effective for quickly returning the associated bell crank lever to normal. In order to accommodate the springs individual to the levers 27 within a given area, two mounting plates 35 and 36 are displaced from each other and are secured to side plates 21 and 22, thereby permitting the springs to be arranged in two rows, as shown in Fig. 3. Individual to each of the levers 27 is a selecting bar 31 which is engaged on its under side by a pin 38 secured to the free end of the bell crank lever 27. The selecting bars have on one surface a plurality of serrations or teeth 32, while on another surface a projection 33 is formed. The end of the bar 31 opposite to that carrying the serrations or teeth 32 is enlarged as indicated by the numeral 34.

The electromagnets 25 upon being energized elevate the bar 31 through the movement of the bell crank lever 27 to a point where the teeth 32 thereof are brought into engagement with a segmental gear 37. This segmental gear 37 is mounted transversely of the selecting bars 31 (Fig. 2) and is secured to a shaft 38 which is journaled in the plates 21 and 22. The shaft 38 (Figs. 2, 3 and 4) carries a gear 39 which is adapted to be oscillated by means of a rack 40 held firmly in engagement with the gear 39 by a flanged roller 41. The rack 40 is secured to an operating bar 41 which has its opposite end secured to one end of a lever 42 which is pivoted at 43. The lever 42 is of the shape shown in Fig. 4 and carries a roller 44 which cooperates with a cam groove 45 for causing the movement of the operating bar 41 and its associated rack 40 in accordance with the rotation of a cam 45. As is clear from the arrangement of the lever 42 and the cam 45 with which the roller 44 cooperates, the rack 40 will be reciprocated and will consequently impart to the segmental gear 37 through the gear 39 an oscillatory movement. Consequently, any of the selecting bars 31 which will be actuated in accordance with the energization of the electromagnets 25 during the oscillation of the segmental gear 37 in a clockwise direction will have the teeth 32 thereof moved into mesh with the teeth of the segmental gear 37 and will be moved to the left, as viewed in Fig. 3, a distance dependent upon the time in the cycle of movement of the segmental gear at which the teeth 32 of the bar 31 engage the teeth of the gear 37. Conversely, when the segmental gear 37 is operated in a counter-clockwise direction the selecting bars 31, which were moved to the left upon the previous oscillation of the segmental gear 37, will be retracted to their normal position.

As previously described, a projection 33 is formed on a surface of the bar 31. This projection normally engages a somewhat similarly shaped portion of a member 46 which extends transversely of the selecting bars 31 and which functions to maintain the selecting bars in en-

gagement with the segmental gear 37 upon their operation by the electromagnets 25 and to disengage the selecting bars from the segmental gear upon their retraction to the position shown in Fig. 3. In further explanation of this operation it will be noted that the under side of the selecting bar 31 has a depressed portion 50 in which the projecting portion of the bar 46 normally rests. When a selecting bar 31 is elevated through the operation of the pivoted bell crank lever 27 and is moved to the left through the oscillation of the segmental gear 37, it will be maintained in operative association with the segmental gear independently of the energization of the associated electromagnet 25, as the surface 51 of the selecting bar 31 now rests on the bar 46. When the selecting bar 31 is retracted due to the oscillation of the segmental gear 37 in a counter-clockwise direction, and when it reaches a position where the groove 50 is in vertical alignment with the bar 46, the lip of the bar 46 will engage the projection 33 and cause the disengagement of the selecting bar 31 from the segmental gear 37.

25 The cam 45 through which the rack 40 is reciprocated is mounted on a shaft 52 which extends transversely of the machine and which is mounted to depending members 48 and 49 below the shaft 38. Also rigidly secured to the shaft 30 52 is a cam 53 which is provided with a cam groove 54 which is engaged by a roller 55. This roller 55 is carried by the free end of an arm 56, which is integral with and mounted substantially central to a shaft 57 (Fig. 2), which 35 carries at its extreme ends arms 58 and 59 having connected thereto vertically extending links 60 and 61. Connected to the opposite ends of the links 60 and 61 is a member or ram 63 which extends transversely of and above the enlarged portion 34 of each of the selecting bars 31 and which is reciprocated on vertical guides 66, 67, 68 and 69. As shown in Fig. 8, the member or ram 63 has a recessed portion 64 in which there is positioned a slotted member 65. This member 40 is secured against movement, but the recess 64 is of a depth sufficient to permit a predetermined vertical movement of the member or ram 63.

45 The ends of the selecting bars 31 having the enlarged portion 34 slide in the slots or grooves 50 formed in the member 65 and are thereby guided when moved to the left or right (Fig. 3) depending upon the direction of rotation of the segmental gear 37. Positioned below the member 65 and secured to and movable with the ram 63 55 is a plate 70 having apertures arranged to receive perforating pins 71. In the particular embodiment of the invention disclosed in the drawings, the perforating pins 71 are arranged in forty-five rows with ten pins to each row, making a total of four hundred and fifty perforating pins 71. Each of these perforating pins is provided with a shoulder 72 which normally rests on the upper surface of the plate 70. When a selecting bar 31 is moved to the left (Fig. 3) 60 a distance depending upon the time at which it was caused to engage the teeth of the segmental gear 37, a perforating pin in the particular row of perforating pins to which a selecting bar 31 is common will be selected for operation. That is, for each movement of the selecting bar 31 only one of the perforating pins 71 of the row of pins to which that particular selecting bar 31 is common will be selected for subsequent actuation, since the enlarged portion 34 thereof 65 is of such dimension as to cover only one per-

forating pin 71. The actuation of the selected perforating pin 71 is effected through the downward movement of the ram 63 by the cam surface 54, which causes the perforating pins 71 to be positively depressed into operative association with aligned apertures 73 formed in a die plate 74 which is rigidly mounted to the base plate 24. Interposed between the die plate 74 and the apertured member 70 are two similarly apertured plates 76 and 77 which are secured to opposite faces of blocks 78 and 79 which are supported by the base plate 24. Inasmuch as the apertures in the plates 70, 76 and 77 are in vertical alignment with the apertures in the die plate 74, the perforating pins 71 will be accurately guided. The plate 77 is spaced from the die plate 74 a distance sufficient to allow the passage of a record sheet or card therebetween. When the cam surface 54 reaches a predetermined position in its rotation, arm 56 will be moved downwardly for causing the upward movement of the ram 63. Plate 70 being moved with the ram 63 and being engaged by the shoulders 72 on the perforating pins 71, elevates the actuated perforating pins to the position shown in Fig. 8.

As is clearly shown in Figs. 1 and 3, the machine is provided with an inclined table 82 which is mounted above and substantially central to the key board 5. The table 82 is arranged to receive a record sheet or card which is desired to be perforated in accordance with certain predetermined operations of the keys in the various groups of keys making up the key board 5.

Following the placement of the record sheet or card on the table 82 and synchronously with the operation of the segmental gear 37, mechanism is operated for automatically advancing the sheet or card to a position below the perforating pins 71. This mechanism comprises a pair of oppositely disposed feed fingers 83 and 84 which, upon being moved, engage the sheet or card and positively advance it along the table 82 to a position where it is engaged by positively driven rollers 85 and 86. While the roller 85 is positively driven it is also pivotally mounted at 87 (Fig. 4) and held in operative association with the roller 86 by means of a coil spring 88. The feed fingers 83 and 84 are operated momentarily by means of a leverage arrangement which is reciprocated in synchronism with the oscillation of the segmental gear 37, by a cam 92 which is secured to the cam 53, but on the opposite side to the cam groove 54. Specifically the mechanism for moving the feed fingers 83 and 84 comprises a pivoted lever having arms 93 and 94. To the arm 93 is secured a roller 95 which engages the cam surface of the cam 92 and which upon such engagement causes the movement of a collar 96 which is mounted loosely on a rod 97. Movement of the rod 97 is effected through a collar 98 rigidly secured thereto and a spring 99 which is interposed between the collars 96 and 98. Operatively associated with the arm 94 is an adjustable screw 100 which limits the movement of arm 93 and insures the proper engagement of the roller 95 with the cam 92. Secured to the end of the rod 97 opposite to the end on which the sleeve 96 is loosely mounted is a bar 101 which extends transversely of the table 82 and to which there is rigidly secured a U-shaped member provided with arms 102 and 103. Each of the arms 102 and 103 carries a link 104 which is normally under the tension of a spring 105 and which is secured to 75

a transversely extending bar 106. The feed fingers 83 and 84 are secured to the bar 106, and since the top of the table 82 is slotted at 107 (Fig. 1), the fingers 83 and 84 are capable of being moved upon the movement of the rod 97 and its associated U-shaped member including the arms 102 and 103.

When the feed fingers 83 and 84 are moved in the manner just described, and provided a record sheet or card had been placed on the table 82, it will be advanced to a position where it is engaged by the rollers 85 and 86, after which the feed fingers will be retracted to a position to receive another card. These rollers (Fig. 5) are driven from the shaft 38 which carries the segmental gear 37 through a train of gears consisting of gears 112, 113, 114, 115, 116, 117, 118, 119, 120, 121 and 122. It will thus be seen that the rollers 85 and 86 which are secured to gears 121 and 122, respectively, will be driven through the train of gears just referred to in synchronism with the oscillation of the segmental gear 37 and will, during the movement of this gear in one direction, be rotated in a direction for moving the record sheet or card into alignment with the perforating pins 71, and in an opposite direction for causing the retraction of the record sheet or card upon the rotation of the segmental gear 37 in a direction opposite to that which caused the forward movement of the selecting bars 31. The advancement and retraction of the record sheet or card is also facilitated by means of the rollers 123-123 and 124-124 which are positively driven through gears 117 and 119, respectively, and which are operatively associated with spring pressed rollers 125-125 and 126-126, respectively. As shown in Figs. 4 and 8, the rollers 125 and 126 are interposed between the plates 76 and 77 having a portion thereof projecting through the plate 77 and are pivotally mounted at 127-127 and 128-128, respectively, resilient means 129-129 being provided for holding the respective rollers firmly in contact with the rollers 123-123 and 124-124. The forward movement of the card is arrested by a stop member 131 located between the die plate 74 and the plate 77. Like the rollers 85 and 86, the rollers 123-123 and 124-124 will be rotated first in one direction to advance the card and then in a reverse direction to retract the card in accordance with the oscillation of the segmental gear 37.

As shown in Fig. 1, the rollers 85 and 86 are provided with cut-out portions 133 to permit the mounting of a spring 134 which is formed with projecting portions 135 which extend into the cut-out portions 133 of the rollers 85 and 86. A card in being advanced by the feed fingers 83 and 84 causes the depression of the spring 134 upon its engagement by the rollers 85 and 86. It will thus be apparent that the projections 135 of the spring 134 are directly in the path of the perforated card as it is being ejected and will cause the card to be diverted along a different path than it traversed upon its advancement to be perforated. When the card is deflected by the projections 135 of the spring 134, the edge thereof strikes a surface 137 of spring pressed members 139-139 which cooperates with a surface of member 138 to cause the card to assume a horizontal position on the bottom of a hopper 136, as shown in Fig. 3.

Power for driving the shaft 52 is communicated from an electric motor (not shown) through a belt 140, and a continuously rotating pulley wheel 141 which is secured to a shaft 142 to

which there is also secured a worm wheel 143 (Fig. 2). The worm wheel 143 engages a worm gear 144 which is rigidly secured to a stud shaft 145. Also secured to the shaft 145 is a serrated member 146 of a clutch mechanism designated generally by the numeral 147. Positioned opposite to and on the driven shaft 52, the shaft 145 being referred to as the driving shaft, is a pivoted member 148. The pivoted member 148 is normally urged to the right, as shown in Fig. 7, by a coil spring 149 mounted in a housing 150 in the free end of the pivoted member 148. A projecting portion 151 of a collar secured to the driven shaft 52 forms a base away from which the spring 149 urges the pivoted member 148. The pivoted member 148 has a resilient wedge-shaped member 152 positioned therein and urged in an upward direction (see Fig. 5) by a spring 153. The pivoted member 148 also has a finger 154 at the extreme end thereof opposite the pivot point. The shaft 52 is supported by supporting member 49 upon which is also mounted an electromagnet 156 having an armature 158 which is urged away from the electromagnet by a spring 159. Formed on the end of the armature 158 is a detent 160 which engages a member 161 pivoted on the support 49.

When the electromagnet 156 is energized, the detent 160 will be moved downwardly (Fig. 7) or to the left, as viewed in Fig. 5, thus releasing the pivoted member 161 which, together with the pivoted member 148, will be moved to the right (Fig. 7), by the action of spring 149. Consequently, the wedge-shaped member 152 will be forced to engage the serrated portion of the continuously rotating member 146. Just prior to the completion of the cycle of rotation of the pivoted arm 148, the projecting finger 154 engages a cam surface 162 mounted on the member 161 for causing the spring actuated detent 160 to engage the pivoted member 161 and restrain it against movement to the right, as viewed in Figs. 2 and 7. In the further movement of the finger 154, cam surface 170 is engaged, thereby resulting in the movement of the pivoted member 148 to the left (Fig. 7) and the disengagement of the wedge-shaped member 152 from the serrated portion of the member 146. The elements just described will remain in this position until the subsequent energization of the electromagnet 156.

In addition to the cams 45 and 53, a gear 164 is also mounted on the driven shaft 52. This gear meshes with a gear 165 which in turn meshes with a gear 166 secured to a stud shaft 167 (Figs. 2 and 6). The stud shaft 167 is mounted parallel to the shaft 52 and has mounted thereon at spaced points contact operating members 168 and 169. These contact operating members preferably consist of insulating and contacting portions which in the course of their rotation are operatively associated with contact brushes 173—173 and 174—174, respectively, which are mounted on opposite sides of the respective contact operating member 168 and 169. As will be described more in detail hereinafter, the contact operating members 168 and 169 control the completion of circuits extending from the contact brushes 173 and 174 and specifically function to insure that the electromagnets 25 will be energized only during the forward stroke of the selecting bars 31 and that the actuating keys of the key board 5 and the operated elements of the computing or multiplying mechanism 6 will be restored to normal.

The completion of circuits established through

the actuation of the keys in the key board 5 and the elements of the computing or multiplying mechanism 6 is effected to the electromagnets 25 of the perforating mechanism 7 through a switching mechanism indicated generally by the numeral 175. The switching mechanism 175 consists of a plurality of arcuate banks of contacts 176 and a brush 177 individual to each bank of contacts 176. Rotation of the brushes 177 which is in synchronism with the oscillation of the segmental gear 37 is effected through a gear 178 which is secured to shaft 179 upon which the brushes 177 are mounted. A rack bar 180 having teeth at each end cooperates with gears 181 and 182 and is held in this position by flanged rollers 181 and 183. The gear 182 is mounted on a shaft 184 which also carries a gear 185 (Fig. 4). Meshing with the gear 185 are the teeth of a rack bar 186 which are held in operative association therewith by a flanged roller 187. The upper end of the bar 186 has teeth formed at right angles to the surface at which the teeth which engage the gear 185 are formed, which teeth engage a gear 188 which is secured to the shaft 38. Intermeshing of the teeth of the gear 188 and the teeth formed on the upper part of the bar 186 is also effected by means of a flanged roller 189. From this description of the switching mechanism 175 it will be seen that circuits which are connected with contacts 190 will be progressively completed upon the rotation of the brush 177 individual to the bank of contacts including the particular contacts connected with the actuated keys of the key board 5 or the elements of the computing or multiplying mechanism 6 which are at that particular time operated.

In further explanation of the switching mechanism referred to generally by the numeral 175, the small rectangles in the upper right hand corner of Fig. 1 designated by the numerals 195, 196, 197, 198, 199 and 200 are intended to indicate the location of switching mechanism similar to that designated by the numeral 175. However, for the sake of clarifying the drawings the details of the switch mechanism in this particular figure have been omitted. Contained in each of the rectangles 195 to 200, inclusive, are a plurality of arcuate banks of contacts with a rotatable brush individual to each bank of contacts. In the specific embodiment of the invention disclosed there are included in the several banks of contacts a total of five hundred and thirty contacts. Of this number four hundred and fifty are connected to the key board 5 independent of the computing or multiplying mechanism 6, while the remaining eighty contacts are allotted to the computing or multiplying mechanism 6. As previously mentioned, the perforating mechanism includes a total of forty-five electromagnets. These electromagnets are adapted to be connected to the brushes of the respective switching mechanisms and are energized momentarily upon the passage of the brush individual thereto over a contact in the arcuate bank of contacts which is at that particular instant connected with battery either directly through the contacts of a depressed key of the key board 5 or the operating elements of the multiplying mechanism 6 and the contact controlling switch 168.

It is believed that a clear understanding of the parts of the apparatus described previously will be had from a detailed description of the operation of the various elements embodied in the ap-

paratus. As previously noted, the key board 5 is preferably divided into a plurality of groups of keys, which groups may be allotted to control the perforation of expressions for certain predetermined information. As shown in Fig. 1, the keys are arranged in rows of ten keys each, the upper key in each row being referred to as the repeat key. That is, when it is desired to perforate a second card or other cards in accordance with a previous setting of the key board, the key designated as the repeat key is depressed, which, as will be more clearly explained herein-after, functions to prevent the release of the previously depressed keys.

Before entering into a detailed description of the operation of the apparatus for a given problem, it will first be explained that the various rows of keys are adapted to control the energization of electromagnets 25. This feature is accomplished by means of groups of jacks designated generally by the numeral 11 and designated specifically by the group numerals 201, 202 and 203 which, for the sake of clearness, will be referred to as the key board jacks, the perforating jacks, and the product jacks, respectively. The group of jacks 201 are connected directly to the contact brushes cooperating with the contacts of the keys of the key board 5, while the group of jacks 202 are connected directly to the windings of the electromagnets 25, and groups 203 are connected directly to the contact brushes cooperating with the output elements of the multiplying mechanism 6.

Assume now that the first five rows of keys and the next three rows of keys of the key board 5 are allotted to the multiplicand and multiplier, respectively, and that it is desired to perforate in a record sheet or card information expressing the multiplicand and multiplier in the form of perforations in the first eight allotted columns of the record sheet or card. In order that the depressions of the multiplicand and multiplier keys will be indicated in these particular areas of the card, flexible cords 14 are employed for interconnecting the first eight jacks in the horizontal row of jacks 201 with the correspondingly numbered jacks in the group of jacks 202. With such circuits established, the electromagnets 25 of the perforating mechanism will be interconnected with the rotating brushes 177 of the first eight banks of arcuate banks of contacts 195, which contacts are connected directly to the contacts of the keys, as indicated in Fig. 10. Let it further be assumed that it is desired to perforate the card in accordance with certain departmental information such as, for example, the department number, and that the next three rows of keys following the row of keys set apart for the multiplier are allotted to the departmental information. In like manner the keys in the last mentioned rows of keys will be interconnected with the rotating brushes 177 of the last two banks of contacts in the arcuate banks of contacts 195, and the first bank of contacts in the arcuate banks of contacts 196 with the electromagnets 25 by means of the flexible cords 14.

The product resulting from the multiplication of the digits of the multiplicand and multiplier may be perforated in any of the remaining areas of the record sheet or card. Although the keys 70 in the first eleven rows of keys have been described as controlling the perforations in the first eleven columns on the card, these keys may be connected by means of the flexible cords 14 so as to effect the perforation of the information 75

in any column. For the purpose of illustration, columns 31 to 38, inclusive, of the card have been set apart to receive the product. The rows of keys for the various digits of the multiplicand and multiplier have additional contacts which are connected directly, as shown in Fig. 10, to the multiplying mechanism 6, which, in turn, has its operating elements connected to contacts of the first eight banks of contacts in the arcuate banks of contacts 200. These contacts may be interconnected with the electromagnets 25 by the rotating brush 177 individual to the particular bank of arcuate banks of contacts connected to the multiplying mechanism 6 by flexible cords 14 connected to the eight jacks of the group of jacks 203 and the jacks numbered 31 to 38 of the group of jacks 202.

Let it further be assumed that it is desired to compute the cost of the work done by a certain department, for example, a department having the number 901 assigned thereto and whose average rate is six dollars and seventy-eight cents (\$6.78) per hour, has done one hundred and thirty-four and one-quarter (134 1/4) hours work. For this particular problem, the keys indicated with a cross (X) on the key board 5 will be depressed. The depressed keys indicate the multiplicand, the multiplier, and the number of the department, respectively.

In order to bring out more clearly the flexibility of a key board of this type, it will be assumed that it is not desired to compute the cost of the work in thousandths and ten thousandths parts of a dollar. To accomplish this object it is necessary to simply connect the jacks 1 to 6 of group 203 to jacks 33 to 38 of group 202, thus dropping the last two decimal points of the product, and shifting the product so that the last denominational column on the card will have perforated therein the one-hundredth part of a dollar in the product.

Referring now to Fig. 10 which shows schematically the circuit connections for one row of keys, this circuit is typical of all of the other rows of keys, excepting those which are not connected with the multiplier 6. As shown in this figure, the contacts of the keys are connected to the contacts of one of the arcuate bank of contacts 176 and the multiplying mechanism 6, which in turn is connected with the contacts of another bank of contacts of the arcuate bank of contacts 176.

In the problem selected for illustration, the key 207 numbered 1, counting from left to right as viewed in Fig. 10, is depressed. The depression of key 207 closes contacts 208 and 209, the contact 208 being connected through conductor 210 to contact 211, of one of the arcuate banks of contacts 176. Contact 209 of the key 207 is connected through conductor 212 to the multiplying mechanism 6. The depression of the key 207 or any of the other keys also causes the bar 213 which is common to all of the keys with the exception of key 214 which is designated as the repeat key, to be moved to the left, as viewed in Fig. 10, for opening contact 215. This operation results due to the location on the bar 213 of pins 216 which are mounted on the left of the respective keys and which are engaged upon the depression of the keys for causing the movement of the bar 213 to the left, resulting in the opening of contact 215 and closing of contact 217. The latter contact is in circuit with the electromagnet 8 which, upon being energized, causes the release of the depressed key in the row of

keys to which the electromagnet 8 is common, as described in detail in the aforementioned patent. The operating circuit of the electromagnet 8 extends from battery through the right hand brush 173 (Fig. 2), the conducting plate 222 of contact member 168, and the right hand brush 173 (Fig. 6), momentarily at a predetermined point in the cycle of rotation of the contact member 168, conductor 223, contact 224, winding of the electromagnet 8, contact 217 (closed on depression of any of keys 1 to 9), and conductor 225 to ground. Likewise, circuits similar to those just described will be established upon the depression of the other keys in the respective rows of keys of the multiplicand and multiplier. In the event that there is no key in any of the various rows of keys depressed, contact 215 is maintained closed, which completes the circuit to contact 218 of one of the arcuate bank of contacts 176 associated with that particular row of keys.

It will be noted that there is no zero key provided in the rows of keys on the key board. However, if it is desired to perforate an aperture in the card in the position allocated to zero, no key need be depressed and the perforation of zero will be automatically accomplished through the contacts of the key structure shown diagrammatically in Fig. 10.

Circuits having been established through the depression of the various keys to the multiplying mechanism 6, the elongated member 15 is depressed, which causes the closure of a starting circuit (not shown) extending to the multiplying mechanism 6. Upon the completion of this circuit, the elements of the multiplying mechanism 6 are set in operation and function to compute the product of the particular problem. The multiplying mechanism having performed its function establishes through its elements, circuits extending to contacts in the various banks of arcuate banks of contacts 200. Also assuming that the arcuate bank of contacts shown schematically in Fig. 10, as associated with the multiplying mechanism 6, is the bank of contacts associated with jack numbered 6 of group of jacks 203, the product which will be transmitted by the multiplying mechanism to the jacks 203 will, in this specific instance, be 910.2150. Since this product will be transmitted to jacks 2 to 8, respectively, of group 203, and further since the jacks 7 and 8 which would have transmitted thereto impulses to control digits 5 and 0, respectively, have not been connected to any of the group of jacks 202, these digits will not be perforated in the card due to this break in the circuit. However, since jack numbered 6 of group 203 has been connected to jack 38 of group 202 by means of the connecting cord 14, the contact 226 will have ground supplied thereto by the multiplying machine. Likewise, contact 211 of another bank of arcuate bank of contacts 176 will be connected to ground but directly through contact 208 of the key 207. In the case of the departmental information, the keys in the rows of keys allotted thereto will establish corresponding circuits to other banks of arcuate banks of contacts 176.

The circuits from the depressed keys and the multiplying mechanism 6 to the various contacts in the several banks of arcuate banks of contacts 176 having been established, elongated member 16 is depressed. The depression of this member completes a circuit (not shown) to the electromagnet 156 which upon being energized actuates detent 160 which allows the member 161 and the

pivoted member 148 to move to the right, as viewed in Fig. 7. The movement of the pivoted member 148 causes the wedge-shaped member 152 to engage a serration in the continuously rotated member 146. Consequently, power is communicated to the shaft 52 from the continuously driven shaft 145, through the serrated member 146 and the pivoted member 148. The shaft 52 in rotating carries with it cams 45 and 53 and gear 164.

The cam 45, as described in detail, actuates the pivoted lever 42 which causes the reciprocation of rack 40 through the operating bar 41. Oscillation of the gear 39 is thereby effected for causing the corresponding oscillation of the segmental gear 37. Synchronously with the oscillation of gear 39, gear 188 which is secured to the same shaft is oscillated for causing the reciprocation of rack bar 180 which, through gear 178, rotates shaft 179 on which the brushes 177 individual to the respective banks of arcuate banks of contacts 176 are mounted. As the brushes 177 pass over the first contacts in each of the banks of arcuate banks of contacts, a circuit will be established to the electromagnet 25 of the perforating mechanism 1, provided ground was previously connected to those particular contacts of the arcuate banks of contacts. However, the completion of the circuits to the electromagnets 25 is controlled by contact switch 168 which is rotated through gear 164 and which connects all of the electromagnets 25 with battery for approximately 150 degrees of its rotation through the right hand brush 173 (Fig. 2), the conducting plate 222 of switch 168, and the left hand brush 173 (Fig. 6).

In the particular example selected for illustration, ground was connected to contacts 211 and 226, which contacts are in different banks of arcuate banks of contacts 176. Consequently, when the brush 177 of these banks of contacts engages contacts 211 and 226, circuits will be momentarily established to the electromagnets 25 which are connected through flexible conductors 14 to the brushes individual to these banks of contacts. The electromagnets 25 upon being energized cause the operation of bell crank levers 27 for elevating the selecting bars 31 individual thereto into contact with the segmental gear 37. The segmental gear 37 now being rotated causes the movement of the selecting bars 31 to the left until they are in vertical alignment with the second perforating pins 71 of the respective rows of perforating pins (Fig. 3). The movement of the selecting bars 31 to the second position is due to the fact that the segmental gear 37 has substantially completed its oscillation in a clockwise direction and due to the fact that the brushes 177 have previously passed over eight contacts 190.

In the specific problem stated hereinbefore for figuring the cost of certain work, the brushes 177 in passing over the contacts 190 will first energize the electromagnets 25 controlling the selector bar 31 associated with the 9th and 34th row of perforating pins 71 and will thereafter, at regular intervals, energize successively the electromagnets 25 which control the selector bars 31 associated with the 8th, 7th, 6th, 5th, 3d, 2nd rows, the 4th and 7th rows simultaneously, the 1st, 11th, 35th, and 38th rows simultaneously, and the 10th and 36th rows simultaneously. Upon the actuation of these electromagnets 25, as pointed out hereinbefore, the selecting bars 31 will be drawn into engagement with and driven forward by the segmental gear 37, and since the electromagnets 25 controlling the 9th and 34th rows of

perforating pins are actuated first, the selecting bars associated therewith will be drawn forward the greatest distance. The other selecting bars will be moved through a distance corresponding to the point in the rotation of the segmental gear 37 at which the electromagnets 25 individual thereto are energized.

During the forward movement of the selecting bars 31, cam 53 is also rotating and brings cam 92 into operative relation with roller 95 which, through rod 97 and its associated elements moves a card 227 engaged by the feed fingers 83 and 84 into association with the rollers 85 and 86 which rollers engage the card and advance it to a position where it is engaged by the rollers 123 and 124. These latter rollers advance the card 227 to a position against a stop 131. Shortly after the movement of the fingers 83 and 84, cam groove 54 of the cam 53 is rotated to a position where the roller 55 is effective to elevate arm 56. The elevation of the arm 56 causes the downward movement of the ram 63, and since the selecting bars 31 are now in their selected position, the perforating pins 71 on which the enlarged portion 34 of the selecting bars 31 rests, will be depressed to cause the card 227 positioned between the die plate 74 and the plate 77 to be perforated as shown in Fig. 9. Upon the continued rotation of the cam 53 and due to the shape of the cam groove 54, the arm 56 will be moved downwardly, causing the upward movement of the ram 63 which carries with it the apertured plate 70 and the depressed perforating pins 71. Further retraction of the perforating pins 71 is prevented due to the slotted member 65.

At this point in the cycle of operation the cam 45 is in a position where the rack 40 is being moved downwardly, resulting in the oscillation of the gear 39 and the segmental gear 37 in a counter-clockwise direction. Consequently, those selecting bars 31 which were moved to the left, as viewed in Fig. 3, will be moved to the right and will be caused to assume the position shown in this figure by the lip of the bar 46. The perforating card 227 is, during the oscillation of the segmental gear 37 in a counter-clockwise direction, moved from beneath the perforating pins 71 due to the rotation of the rollers 123 and 124 in a counter-clockwise direction. Due to the location of the projections 135 of the spring 134, the perforated card 227 will be deflected into the hopper 136. Also synchronously with the oscillation of the gear 39 the gear 178 is oscillated in a direction to restore the brushes 177 of the several banks of arcuate banks of contacts 176 to normal.

Just subsequent to the time the selecting bars 31 reach the extreme point in their movement to the left (Fig. 3), contact switch 167 is effective for causing the release of the operating elements of the multiplying mechanism 6 in a manner more fully described later in the specification. Also following the opening of the circuits to the electromagnets 25 and about the same time that the contact switch 167 is effective, contact switch 168 completed a circuit extending to the electromagnets 8 of the various rows of keys in the key board 5. Provided the repeat key 214 has not been depressed, the electromagnets 8 will be energized over a circuit previously traced, causing the restoration of the depressed keys.

Inasmuch as the previously depressed keys have been returned to normal, the machine is 75

in readiness to receive a new problem. The fingers 83 and 84 being at that time in their retracted position or the position shown in Fig. 1, an unperforated card may be associated therewith for subsequent advancement to a position where it will be perforated. The operator may now depress the desired keys in accordance with the new problem to be computed, the product of which will be perforated in the card now positioned on table 82.

Just previous to the completion of the cycle of rotation of the shaft 52, the finger 154 engages the wedge-shaped surfaces 162 and 170 for restoring the detent 160 to normal and disengaging the wedge-shaped member 152 from the serrations of the member 146, thereby stopping shaft 52 and its associated mechanism.

Although this invention contemplates the use of a perforator of the type described in detail hereinbefore in combination with any one of a number of well known types of calculating machines, a preferred computing mechanism, which has been designated generally by the numeral 6, will now be described.

The bank of five keys which have been allotted to the multiplicand and the bank of three keys which have been allotted to the multiplier are designated generally by the numerals 300 and 301, respectively. These banks are represented schematically in Fig. 11 by coordinate groups of lines, the vertical lines or columns from right to left denoting units (U), tens (T), hundreds (H), ten-hundreds (TH), and ten-thousands (TT) and the nine rows of cross lines designating the digits 1 to 9 consecutively. Each intersection of the lines represents an electrical contact, normally open, which can be closed by the actuation of its associated key 207 on the keyboard.

Any particular problem of multiplication can be set up on the key banks 300 and 301 by closing the contacts at the points corresponding to the digits in the multiplicand and multiplier. These contact closures complete electrical circuits through a multiplying commutator 305 and send electrical impulses to a distributor switch denoted generally 306 which directs the impulses to an accumulator 307 for properly accumulating the results.

The multiplying commutator 305 comprises an electrical multiplication table in which there are nine sets, designated as 303, of nine each of electrical contact disks insulated from each other and divided into twenty-seven units of three each, designated by the numeral 304, so adapted that each contact represents one of a series of numbers representing the product of each digit times itself and each other digit running from 01 to 81. Each of the nine sets 303 of nine contact disks represents the numbers 1 to 9 consecutively and are connected to individual conductors leading to the corresponding digit in the multiplicand key bank 300. The contact disks are insulated from and secured to a rotating shaft 308 journaled in bearings 309-309 fastened to a frame 310 (Fig. 13). The shaft 308 is rotated by means of a gear 315 fastened thereto and meshing with a spur gear 316 of a speed reducer 317 which is driven by a belt 318 from a motor 319 rigidly secured to the frame 310. Each unit 304 of three contact disks is also provided with an associated feed disk 340 (Fig. 16) for making connections with the digit cross lines of the multiplicand key bank. The contact disks have individual brushes and are so constructed that

the position of the contact on one-half of the circumference represents the unit number of the particular product of two digits and a contact on the other half the tens part.

Figs. 16 and 17 show one of the units 304 of three disks 325, 326 and 327 representing the products of multiplying 2 by 1, 9, and 2, respectively. These disk units 304 are similar in construction to sequence switches commonly used in telephone exchange systems. The three copper disks 325, 326 and 327 are mounted on an insulator 328 and are electrically interconnected due to the fact that the disks 326 and 327 are integral and are connected with the disk 325 by means of copper rivets 329 passing through the insulator and serving to hold the elements together as the unit 304. The insulator 328 is keyed to the commutator shaft 308 and insulates the associated copper disks therefrom. Disk 325 has one radial contact 332 representing the product 02 of 2×1 to be engaged by a brush 333 at a predetermined point in the rotation of the unit 304; the disk 326 has two radial contacts 334 and 335 representing the tens digit 1, and the units digit 8 of the product 18 of 2×9 to be engaged by a brush 336; the disk 327 has a contact 337 representing the product 04 of 2×2 to be engaged by a brush 338. A feed brush 339 contacts continuously (a triangular headed arrow denotes a brush which is always in contact) with the feed disk 340 which is shown in Fig. 16 as being integral with disk 325. The brushes, as shown in Figs. 11 and 18, are connected through conductors to the multiplicand and multiplier key banks. The above described unit was selected for purposes of illustration and it will be understood that the other units are of similar construction and are analogous to sequence switches used in telephone systems.

Fig. 18, the enlarged fragmentary schematic of the multiplying commutator, shows the arrangement of the multiplication table for three of the sets 303 representing the digits 1, 2 and 3. The multiplication table as illustrated follows the series of 1×1 , 1×9 , 1×2 , 1×3 , 1×4 , 1×5 , 1×6 , 1×7 , and 1×8 ; 2×1 , 2×9 , 2×2 , 2×3 , 2×4 , 2×5 , 2×6 , 2×7 , and 2×8 ; 3×1 , 3×9 , 3×2 , etc., wherein each of the contacts represents a particular product. The multiplication table follows the usual order except that the digit 9 is placed between the digits 1 and 2 to simplify the interconnecting of the circuits. It will be clear that the multiplication tables for the numbers 4 to 9, inclusive, are followed in a similar manner throughout the length of the multiplying commutator.

Secured to the multiplying commutator shaft, but electrically insulated therefrom, is a control commutator 345 (Fig. 12) consisting of circular switches K, L, and M for closing and opening various circuits at predetermined intervals throughout the multiplying cycle, the full purpose of which will become apparent as the description progresses.

A dial 346 (Fig. 13) attached to the commutator shaft 308 and rotatable therewith is divided or marked to indicate twenty-eight equal parts so that each division marking indicates a particular rotative position of the shaft 308 and its associated disk units 304 rigidly mounted thereon relative to a fixed starting point. The positions one to twenty-eight are adopted to more clearly describe the sequence of events as the multiplying commutator 305 passes through one complete revolution, and it is to be noted at

this point, as previously mentioned, that the units part of a product of two digits is registered during the first half revolution of the multiplying commutator; that is, positions one to fourteen, inclusive, and during the second half of the cycle, positions fifteen to twenty-eight, inclusive, the tens parts is registered where the product consists of two digits (more than nine).

The distributor switch 306 (Fig. 11) is provided for transferring the electrical connections from units to tens, tens to hundreds, hundreds to ten-hundreds, etc., as the multiplication progresses to complete an electrical circuit to the proper electromagnets in the accumulator 307. The distributor switch is similar in design to selector switches used in telephone systems and comprises in general a shaft 347, an electromagnet 348 (Fig. 12) for rotating it one step at a time, six brushes 349 to 354, inclusive (Fig. 11), insulatively mounted on the shaft, and arcuate banks 344 of twenty-two stationary contacts adapted for cooperation with said brushes. Five of the brushes 349 to 353, inclusive, designate and may be connected by conductors to the units (U), tens (T), hundreds (H), ten-hundreds (TH), and ten-thousands (TT), columns in the multiplicand key bank 300. The sixth brush 354 applies ground progressively to one of the columns indicating units (U), tens (T), and hundreds (H), in the multiplier key bank 301 as the multiplication progresses to close the circuit therefrom through the multiplying commutator 305, multiplicand key bank 300, distributor switch 306, and the accumulator 307 to battery and ground. The accumulator 307 can be remotely situated from the multiplicand and multiplier key banks to accumulate products of the multiplication, and comprises eight rotatable brushes 360 to 367, inclusive, representing units (U) to ten-millions (TM) columns in the final product, respectively, which brushes are adapted to make wiping engagement with an arcuate bank of contact 368 having stationary terminals number 1-2-3-4-5-6-7-8-9-0. The stopping of a brush on a particular terminal indicates that the number marked on the terminal at which the brush has stopped, has been accumulated in the accumulator and therefore that the accumulator 307 accumulates digits proportional to the length of time the brushes 360 to 367 are rotated.

The rotation of the accumulator brushes 360 to 367, inclusive, is accomplished by an electromagnetically operated means which will now be described. Referring to Figs. 12, 13, 14, and 15 of the drawings, a shaft 371 suitably journaled on the frame 310 has a gear 372 secured thereto meshing with an idler gear 373 which in turn meshes with the gear 315 driving the shaft 308 of the multiplying commutator 305. The rotating shaft 371 has rigidly mounted thereon a plurality of spaced gears 374 adapted to drive gears 375 (Figs. 13 and 14) fastened to shafts 376 carrying loosely mounted sleeves 377 to which the brushes 360 to 367 are rigidly secured. Slidably keyed to and rotatable with the shaft 376 is a clutch member 378 having a serrated face 379 for engaging a companion serrated face 380 of the sleeve 377 to cause rotation thereof. The slidable and rotating clutch member 378 is provided with a groove 384 into which extends the bifurcated end of an armature 385 of an electromagnet 386 of any suitable type. A compression spring 387 is associated with the armature 385 to separate the driving clutch member 378 from

engagement with the brush carrying sleeve 377 when the electromagnet 386 is deenergized. From the foregoing it will be obvious that the energizing of the electromagnet 386 will move the armature 385 thereof to compress the spring 387 and lock the serrated faces of the clutch member 378 and the sleeve 377 together to cause the rotation of its associated brush.

An index or register wheel 388 integral with each sleeve 377 has a series of twenty depressions on its periphery, which depressions are adapted to be engaged by a roller 389 mounted on a compression leaf spring 390 to center the brush with respect to the position of the stationary terminals in the arcuate bank 368. Each depression has a number engraved therein starting with 1 and running consecutively as 2, 3, 4, 5, 6, 7, 8, 9 and 0 so that there are provided two complete sets of indicating numbers on each register wheel. These numbers are so positioned on the periphery of the wheel that the depression immediately above the roller 389 indicates the number designated by its associated brush. For example, in Fig. 14 the brush 367 has stopped on the terminal 9, and the operator by looking at the depression 391 immediately above the roller, reads the number 9 engraved therein. The use of the two complete sets of indicating numbers on each register wheel 388 gives a rapid indication in that a digit is registered for each half revolution of the register wheel.

In order to facilitate an understanding of the working relationship of the details of the computing system and to afford a more effective means of describing many important functions thereof such as the carry function of the accumulator and its method of simultaneously carrying tens to higher denominational orders, an explanation will be given of the steps performed in a specific example such as multiplying 72293 by 159. It will be noted at this time that the problem selected for illustrating the operation of the multiplying mechanism is not the same as that selected for illustrating the operation of the perforating mechanism. However, the problem selected for illustration in connection with the perforating mechanism was of the type which brought out most clearly the operation of the machine from a practical standpoint and the problem selected for illustrating the operation of the multiplier is taken for the reason that it discloses clearly such features as the carry function of the accumulator and the multiplication of a multiplicand by a multiplier having the digit 9 in one of its denominations.

In order to accomplish this multiplication the driving motor 319 (Fig. 13) is connected to a suitable source of power (not shown) to cause continuous rotation of the multiplying commutator 305 and of the shaft 376 of the accumulator switch 307 as has been previously described. Keys 207 on the keyboard 5 (Fig. 1 shown diagrammatically in Fig. 11) in the multiplicand and multiplier key banks 300 and 301 corresponding to the numbers 72293 and 159, respectively, are then depressed as indicated by the circles (Fig. 11) to close electrical circuits at those points. The operator then momentarily presses the start key 15 which closes a circuit from grounded battery 396, conductor 397, and the winding of a starting relay 398 to ground. Relay 398, upon being energized, establishes a locking circuit for itself from ground through its winding and right hand contact and armature, conductor 399 and the winding of the elec-

tromagnet 348 of the distributor switch to grounded battery. The current flowing through the distributor magnet 348 at this time is not sufficient to operate it, but it is sufficient to maintain relay 398 energized. The closure of the left hand contact of relay 398 connects brush 4 of the circular switch M of the control commutator 345 to ground, through conductor 401, conductor 450 and the back contact of clearout switch 402.

10 When the control commutator 345, which runs continuously as a part of the multiplying commutator 305, reaches position 1, as indicated by the dial 346 (Fig. 13), a circuit is established through brushes M4 and M2, conductor 403, left hand winding of a pickup relay 404, conductor 413 and the back contact and armature of a release relay 405 to grounded battery. Pickup relay 404 is thereby energized and establishes a locking circuit for itself through its right hand inner contact.

15 The operation of the pickup relay 404 also establishes a circuit from ground through brushes L4 and L2 of the control commutator 345, conductor 409, left hand inner contact of relay 404, conductor 410, conductor 399 to the winding of distributor switch magnet 348. The circuit just traced is closed for 25° of rotation from position 1 of the control commutator and performs two functions; it operates the distributor switch magnet 348, advancing the distributor brushes 349 to 354, inclusive, to stationary terminals 1 in the plurality of banks 344; and causes the short circuiting of the winding of the starting relay 398 to thereby open its contacts and render the relay ineffective in the circuit. The pickup relay 404 also establishes a circuit from brush L3 conductor 411, left hand outer contact of relay 404, conductor 408, conductor 412 to brush 354 of the distributor switch 306; the pickup relay 404 also establishes another circuit from battery through the contact of release relay 405, conductor 413, right hand outer contact of relay 404, conductor 414, the winding of a carry relay 415, conductor 445, brushes K3 and K4 to ground. The entire operation up to this point is a preliminary or preparatory function to start the multiplying operation at the proper place in the cycle.

20 The beginning of the actual multiplying operation occurs at rotative position 4 of the multiplying and control commutators when brush L3 makes contact and applies ground which will hereinafter be termed as the master ground. Ground is thereby established from brushes L4 and L3 through conductor 411, left hand outer contact of pickup relay 404, conductor 408, conductor 416 and the winding of a relay 417 to grounded battery. The operation of relay 417 closes contacts to complete individual circuits from the units (U), tens (T), and hundreds (H), etc., columns in the multiplicand key bank 300 to their respective brushes 349 to 353 of the distributor switch 306. At the same time the master ground is supplied to the units column in the multiplier key bank 301 through brush 354, terminal 1 of its associated bank 344 and conductor 418. Contact 9 in the units column of the multiplier key bank 301 being closed due to the depression of that particular key, the master ground is continued through conductor 422 to a contact in each of the nine sets 303 of the multiplying commutator 305. This contact in each case as previously described is so cut that it is closed in the first half of the cycle, positions 1 to 14, inclusive, at a point representing the digit

in the units (U) column of the product of 9 times the number of the set.

The ground from the contact 9 of the units (U) column in the multiplier key bank 301 is thus continued on through the various multiplying commutator junctions at the contacts representing the various digits of the products to the corresponding digit cross-lines of the multiplicand key bank 300. At this point the circuit from the master ground finds digit cross-lines connected through to the distributor switch 306 according to the specific problem set up on the multiplicand key bank 300. The first closure in the first half cycle is in the 2 set of the sets 303; that is, 9 times 2 which closes at rotative position 7. An illustration of the specific construction of the unit 304 having disks representing the products of multiplying 2 by 1, 9, and 2 can be had by referring to Figs. 16 and 17 of the drawings wherein the disk 326 has a radial contact 335 representing the units digit 8 of the product 18 of 2 times 9, which contact at rotative position 7 of the multiplying commutator makes a wiping engagement with a brush 336 connected to the conductor 322 (Figs. 11 and 18). As previously explained, the disk 326 is electrically connected through copper rivets 329 to a feed disk 340. This feed disk contacts continually with a feed brush 339 which is connected to a conductor 424 establishing a circuit to the digit 2 cross-line in the multiplicand key bank. In accordance with multiplicand 72293 and the problem assumed the hundred (H) and ten-hundred (TH) columns in the multiplicand key bank 300 are connected to the digit 2 cross-line, connecting the master ground at this time to conductors 425-426, the hundreds (H) brush 351 and the ten-hundred (TH) brush 352 of the distributor 306, which brushes being on terminals 1 of the banks 344 continue the ground through conductors 427-428, conductors 429-430 to the hundreds (H) and ten-hundreds (TH) electromagnets 386 of the accumulator 307, through conductor 431 to battery. These hundred (H) and ten-hundred (TH) electromagnets 386 operate, engaging their clutches 378 (Fig. 15) and starting rotation of the hundred (H) and ten-hundred (TH) brushes 362 and 363 (Fig. 12). At the same time hundred (H) and ten-hundred (TH) holding relays 436 (Fig. 1) are operated over the same path and parallel with the accumulator magnets 386. The holding relays lock through their own contacts to conductor 416, conductor 408, left outer contact of the pickup relay 404, conductor 411 to the brushes L3 and L4 in the control commutator, thereby holding the master ground to the hundred (H) and ten-hundred (TH) accumulator magnets when the contact 335 of the disk 326 opens its circuit an instant later by rotating out of engagement with the brush 336.

One position later in the cycle, position 8, a brush 342 (Fig. 18) connected to the conductor 322 finds a contact enclosure, representing the units digit 7 of the product 27 of 9 times 3, through one of the disk units 304 in set 3 of the multiplication sets 303, through conductor 439, contact closure between the digit 3 cross-lines and the units (U) column in the multiplicand key bank, conductor 440, left outer contact of relay 417 to the units brush 349 of the distributor switch 306. Since the brush 349 is resting on terminal 1 of the associated bank 344, the circuit is continued through conductor 441, units (U) 75

electromagnet 386 of the accumulator, conductor 431 to battery.

The energization of this units magnet 386 operates its associated clutch 378 and consequently causes the rotation of brush 360. At the same time the units (U) holding relay 436 locks through its own contact to keep the units (U) operated after the 9 times 3 contact in the multiplying commutator has been opened. At position 12 the junction of 9 times 7 finds itself connected through the ten-thousands (TT) magnet and operates and locks it. At position 14 the 9 times junction operates and locks the tens (T) magnet in the same manner. One unit of rotation after this which is position 15, the contact of the L3 brush is opened to break the master ground which has maintained all of the accumulator magnets 386 and relays 436 operative allowing the clutches 378 to release. The TT, TH, H, T, and U accumulator brushes 364, 363, 362, 361 and 360 have been carried ahead 3, 8, 8, 1, and 7 spaces representing the units part of the products of 9 times 7, 2, 2, 9 and 3, respectively.

When the commutators 305 and 345 have rotated to position 15 the K3 brush of the control commutator 345 closes a circuit from ground, through brushes K4 and K3, conductor 445, the winding of the carry relay 415, conductor 414, right outer contact of relay 404, conductor 413, back contact of the release relay 405 to battery and thus energize and operate the carry relay 415. The operation of the carry relay 415 is for the purpose of searching for a tens carry to be effected in a manner to be described. Since only the units part of the result of multiplying the multiplicand by the units digit in the multiplier has been registered in the accumulator 307, no brush of the accumulator has passed over 9 and no tens carry results at this time. Also, at position 15 the L2 brush closes for 25° operating the magnet 348 and advancing the distributor brushes 349 to 354, inclusive, to terminals 2 in the banks 344. The system is now ready to proceed with the registering of the tens part of the aforementioned multiplication of 9 times 7, 2, 2, 9, 3.

At rotative position 18, the L3 brush again closes to the master ground and the distributor brush 354 directs the ground to the units (U) column of the multiplier key bank 301 because terminals 1 and 2 of the associated banks 344 are connected together. The previous operation of the clutches 378 is repeated except that the second half of the cycle, positions 15 to 28, inclusive, represents the tens part of each product; that is, the digit 8 of 9 times 9, the digit 6 of 9 times 7, the digit 2 of 9 times 3, the digit 1 of 9 times 2, and the digit 1 of 9 times 2. The distributor brushes 349 to 353 have been advanced to terminals 2 so as to connect the units (U) column of the multiplicand key bank 300 and its associated units (U) holding relay 436 to the tens accumulator magnet 386, through conductor 440, distributor brushes 349, terminal 2, conductors 446 and 447, the winding of the tens (T) accumulator magnet to battery; in a similar manner the tens (T) column of the multiplicand key bank is connected to the hundreds (H) accumulator magnet; the hundreds (H) column to the ten-hundreds (TH) accumulator magnet, etc. This effects the rotation of the proper accumulator brushes to register the tens digits or parts of 9 times the multiplicand 72293 and is completed at rotative position 28 when the L3 brush opens the

master ground on the control commutator 345. The multiplication accomplished up to this point is as shown:

TM	M	HT	TT	TH	H	T	U	Denominations
				7	2	2	9	3
							9	
6	1	3	8	8	1	8	2	7

The action of the TT, TH and H accumulator brushes 364, 363, and 362, respectively, in the first cycle of the assumed problem affords an illustration of the method of carrying tens to higher denominational orders and will be described in detail. As already explained, the TT, TH, H, T and U accumulator brushes receive 3, 8, 8, 1 and 7, respectively, in the first half of the cycle; and in the second half of the cycle the HT, TT, TH, H and T brushes receive 6, 1, 1, 8 and 2, respectively. Now it will be noted that the H brush 362 has received 8 and 8 totaling 16, but has stopped on terminal 6 in the arcuate bank 368. However, in passing from terminal 9 to terminal 0, the brush 362 may contact with an added terminal 448 in the bank 368. This terminal 448 is connected to a relay C2 which is operated over the following circuit; from battery at the C2 relay, through its winding, conductor 449, through the added terminal 448, through the associated brush 362, conductor 450, the back contact of the clearout switch 482 to ground. Upon operation, the C2 relay locks from battery through its winding, through its right contact, conductor 451, and to ground through brushes K1 and K-4 of the control commutator 345 when rotating between positions 20 and 4. In the meantime, the ten-hundreds (TH) accumulator brush 363 has received digits 8 and 1, stopping upon terminal 9 of the associated arcuate terminal bank 368 and the ten-thousands (TT) accumulator brush 364 has received the digits 3 and 1, stopping upon terminal 4. As rotative position 1 arrives, the L3 brush opens the circuit from the master ground, causing the actuated accumulator brushes to stop rotating and releasing the relay 417 (Fig. 11), thereby disconnecting the accumulator magnets 386 from the multiplicand key bank 300 and the associated holding relays 436. At rotative position 1 the K3 brush operates the carry relay 415 over the path previously described, and at position 2 the K2 brush supplies ground to each of the left hand armatures of the C1 to C6 relays, through a circuit from brush K2 of the control commutator 345, conductor 452, to the left hand contact of the relays C1 to C6. Since only the hundreds (H) accumulator brush 362 has passed from 9 to 0, the C2 relay alone is operated, and the ground from the K2 brush passes from the left armature of the C2 relay, conductor 453, right outer contact of relay 415, conductor 454, to the winding of the ten hundreds (TH) accumulator magnet 386 which is operated. At rotative position 4 the K2 brush opens the above circuit, releasing the ten hundreds (TH) clutch 378 after the ten-hundreds (TH) brush 363 has been rotated or advanced 1 unit to the next higher number. This is the tens carry function which transfers one digit to a register of the next higher order when the next lower register passes from 9 to 0.

The mode of accomplishing a plurality of tens carries simultaneously to the next higher denomination is illustrated by the ten-hundreds (TH) 75

accumulator brush 363. It is to be noted at this point that the ten-hundreds (TH) brush 363 has received 8 and 1, totaling 9, at the same time that the hundreds (H) brush 362 received 8 and 8, totaling 16, so that it will be seen that the ten-hundreds (TH) brush 363 came to rest on terminal 9 before the carry operation of the tens digit 1 from the total 16 on the hundreds (H) brush.

10 Referring to Fig. 12, contact disks 460 to 467, inclusive, are shown on the schematic directly under each of the accumulator brushes 360 to 367, inclusive, respectively. These disks are of a construction similar to the aforementioned sequence switches and are secured to the sleeves 377 and rotated with their respective accumulator brushes as illustrated in Fig. 15. Each of the disks comprises an insulator with superimposed pieces of conducting material formed thereon to provide contacts at proper times between 3 brushes Z, F and 9, respectively, except the disks 460, 461 and 467 which have only the brushes Z and F. The feed brush F is always in contact and the brush designated as 9 is connected when, and only when, the associated accumulator brush is standing on the 9 terminal in the companion bank 368. This arrangement establishes a circuit whereby the carry current which was connected to the ten-hundreds (TH) accumulator magnet 386 is conducted also to the ten-thousands (TT) accumulator magnet and the two magnets operate simultaneously due to the fact that the ten-hundreds (TH) accumulator brush 363 was standing on the 9 terminal when the carry current was directed thereto. Starting at the point where the ten-hundreds (TH) accumulator magnet is energized to carry the tens digit 1 of the product 16 from the hundreds (H) accumulator brush 362, the simultaneous carry circuit is traced as follows: The winding of the ten-hundreds (TH) accumulator magnet, conductor 454, brushes F and 9 of the disk 463, conductor 469, right hand middle contact of carry relay 415, conductor 470, the winding of the ten-thousands (TT) accumulator magnet, conductor 431, to battery to thereby operate the ten-thousands (TT) accumulator magnet at the same time that the ten-hundreds (TH) accumulator magnet is operated. If a succession of the accumulator brushes were standing on terminals 9 and a carry current was supplied to the accumulator magnet of the one of the lowest order, all of the accumulator brushes of the higher ones would advance and indicate 0 simultaneously. 55 This carry function is effected only during that part of the cycle reserved for the tens carry, namely, rotative positions 1 to 3, inclusive, and positions 15 to 17, inclusive. This is true because the carry function is controlled by the carry relay 415 which is operated only during that part of the cycle named.

60 During the period that the carry function was being performed, the L2 brush in rotating from positions 1 to 3 had closed a circuit previously described to energize the electromagnet 348 and advanced the distributor brushes 349 to 354, inclusive, from terminals 2 to terminals 3 in their respective banks 344. At position 4 the L3 brush makes contact with the master ground through conductor 411, left hand outer contact of relay 404, conductor 408, conductor 412, distributor brush 354, associated terminal 3, conductor 475 to the tens column of the multiplier bank 381. Since the digit 5 cross-line is connected with the tens column, the ground is extended through

conductor 416, the winding of a multiplier relay 477 representing digit 5, to battery. The operation of the relay 477 closes all of its leads to the proper junction points on the multiplying commutator 305 to ground. As a multiplying commutator rotates and makes contacts for the units part of the results of 5 times 7, 2, 2, 9 and 3, respectively, ground from the armatures of the multiplier digit 5 relay 477 is connected to the denominational columns in the multiplicand key bank 300 through contact closures to the proper digit cross-lines, through the contacts of relay 417 to the corresponding brushes 349 to 353, inclusive, of the distributor switch 306. This switch is now on terminal 3 and the HT, TT, TH and T accumulator magnets 386 and associated holding relays 436 are operated at the proper times to accumulate 5, 0, 0, 5 and 5 on the brushes 368, 364, 363, 362 and 361, respectively, of the accumulator 307.

At position 15 accumulator magnets 386 are released, the carry relay 415 operates and any required tens carry is made as previously described. At the same time the distributor switch 306 is advanced to terminal 4 by the L2 brush of the control commutator 345 closing a circuit from battery to ground and operating the electromagnet 348. During the next half cycle, positions 15 to 28, the tens part of each of the products of 5 times 7, 2, 2, 9 and 3 are registered as described above, except that the distributor switch, being on terminal 4, now routes them to accumulator magnets M, HT, TT, TH and H (Fig. 12) after the tens part of the products of 5 times 7, 2, 2, 9 and 3 are registered as just described, the tens carry function is again performed, the distributor switch is advanced to terminal 5 and the multiplicand 72293 is multiplied by the hundreds digit 1 of the multiplier in a manner analogous to that described for the multiplier digits 9 and 5. The distributor switch is then advanced to terminal 6 and the final tens carry is performed.

Upon completion of this cycle the product of 72293 multiplied by 159 or 11,494,587 is standing in the accumulator 307 and the distributor switch 306 is advanced to terminal 7 by the L2 brush of the control commutator, completing the circuit to energize the electromagnet 348. As the L3 brush makes contact at position 4, the master ground is routed by distributor brush 354 through terminal 7 of its associated bank 344, conductor 480, the winding of the release relay 405 to battery and ground. The operation of the release relay opens its back contact and thereby removes battery from the pickup relay 404, releasing it and restoring all parts of the system to normal except the accumulator brushes which remain in position to indicate the product of the multiplication performed.

It is to be noted that no multiplier relay 477 is operated when multiplying by digits 1 or 9, but there is one provided for each of the multiplier digits 2, 3, 4, 5, 6, 7 and 8. These relays are used to prevent errors which in some instances might occur through the connecting circuit for one digit while multiplying by another digit if these relays or similar means were not provided; that is, the relays 477 are so arranged that two connected unused multiplier circuits cannot make electrical contact closures through the commutator simultaneously.

The terminals 1, 2, 3, 4, 5, 6, 7, 8, 9 and 0 of each bank 368 are connected to the perforating apparatus by a plurality of conductors 485 to the

correspondingly numbered terminals in the arcuate banks 176 forming a part of the group of banks of contacts 200. In this manner the result of a problem is automatically directed to the perforating mechanism and thereafter may be perforated in a record card since ground is normally connected from the back contact of the clearout switch 402 through conductor 450, the brushes 360 to 367 which have been moved into engagement with one of their associated terminals the conductors 485 to the terminals on the banks 176 of the group 200.

The clearout switch 402 which is shown schematically in Fig. 12 normally connects ground through the accumulator brushes 360 to 367 to the terminals in the arcuate banks 176 so that upon the actuation of the elongated member 16 the perforating mechanism will begin its cycle of operation to perforate the factors of the problem set up on the keyboard and the result thereof in the record in the manner described hereinbefore in connection with the perforating mechanism and after the perforating mechanism is set up to perform the perforating operation the clearout switch 402 will be operated by the switch 167 to energize the relays 482 and 483 for connecting ground to the electromagnets 386 to cause them to connect their associated brushes 360 to 367 to the drive mechanism therefor for driving the brushes to a position where they will engage terminals 0 of their associated banks at which time the circuit to the electromagnets 386 will be broken at brushes Z of the contact disks 460 to 461.

What is claimed is:

1. A perforating mechanism comprising a plurality of groups of perforating members, an element associated with each group of perforating members for actuating any perforating member in the group, means for advancing the elements into operative association with a perforating member, means for determining the relation of the last mentioned means and the element, means cooperating with the elements associated with each group of perforating members for operating the perforating members in accordance with the operation of the elements, a multiplying mechanism for controlling the determining means, and control means operable to store information for subsequently controlling the operation of the multiplying mechanism and the determining means.

2. In a perforating apparatus, means for setting up a multiplicand and a multiplier, means connected with the setting up means to effect a multiplication, means including a plurality of perforating members controlled by the aforementioned means for perforating a multiplicand, a multiplier, and the product thereof in predetermined areas of a record sheet, and means for determining the location of the perforations representing multiplicand, the multiplier and the product thereof in the record sheet.

3. In a perforating apparatus, means for setting up a multiplicand and a multiplier, means connected with the setting up means to effect a multiplication, means including a plurality of perforating members selectively controlled by the aforementioned means for perforating a multiplicand, a multiplier and the product thereof in various areas of a record sheet, and means for electrically connecting the setting up means and the multiplying means to the perforating means so that the perforations representing the multipli-

cand, the multiplier and the product thereof may be perforated in any area of the record sheet.

4. In a perforating apparatus, means for setting up a multiplicand and a multiplier, means connected with the setting up means to effect a multiplication, and means for perforating the digits of the problem in a record sheet comprising a plurality of perforating members, electrically controlled means for selecting the perforating members for actuation, and selector switches operable by the setting up means and the multiplying means for controlling the operation of the selecting means.

5. A combination perforating and calculating mechanism comprising digit setting means, means controlled by the digit setting means for effecting a multiplying computation, means controlled by said last mentioned means for establishing electrical connections representing the result of a multiplying computation, a plurality of selector switches some of which are connected to the digit setting up means and others of which are connected to the means for setting up electrical connections representing the result of a multiplying computation, a plurality of perforating members, elements associated with the perforating members for selectively actuating them, means for advancing the elements into operative association with the perforating members, and means controlled by the selector switches for conditioning the elements for advancement.

6. In a perforating mechanism, a plurality of perforating members, selecting means for controlling the actuation thereof, means for controlling the operation of said selecting means to determine the perforating members to be actuated thereby, a multiplying mechanism for controlling some of said last mentioned means, and means operable to establish circuits to control other of the means for controlling the operation of the selecting means and to simultaneously set up factors of a problem in the multiplying mechanism.

7. In combination with a mechanism for effecting multiplying computations electrically, a perforating apparatus comprising a plurality of perforating members, selecting elements for determining the perforating members to be actuated, means for entering information and for setting up the digits of a multiplying computation in the computing mechanism and for controlling some of the selecting elements, control means for taking information from the computing mechanism to control some of the selecting elements comprising a group of selector switches actuated by the computing mechanism, and a second group of selector switches connected to said group of selector switches controlled by the computing mechanism and means for actuating the selecting elements as controlled by the said control means to operate the perforating members.

8. In a perforating mechanism, a plurality of perforating members, electromagnets for controlling the operation thereof, means for controlling the operation of the electromagnets comprising a plurality of selector switches, a multiplying mechanism, factor storing means for controlling the computing mechanism and energizing some of the selector switches, and means in the multiplying mechanism for energizing other of the plurality of selector switches.

9. In a combination computing and recording apparatus, setting up means for storing a plurality of factors of a problem of multiplication, means connected with the setting up means to

effect a multiplying computation, means including a plurality of recording members controlled by the setting up means for recording the factors in a record sheet and by the computing means for recording the result in the record sheet, and means intermediate said setting up means and said recording members and intermediate said computing means and said recording members for predetermining the location of the recordings representing the factors and the result thereof in any desired area of the record sheet.

10. In a combination computing and recording apparatus, means for storing the factors of a problem of multiplication, computing means connected with the storing means, means including a plurality of recording members controlled by the computing means and the storing means for recording the factors and the result of the multiplication in various areas of a record sheet as individually controlled by the computing means and by the storing means, and means interconnecting the storing means and the recording means so that the separate factors and the result thereof may be recorded in any predetermined area of the record sheet.

11. In a recording apparatus, setting up means for storing the factors of a problem, means connected with the setting up means to effect a multiplication of the factors, and means for recording the factors and the result thereof in a record sheet including a plurality of recording members, elements for selecting the recording members for actuation, means for moving predetermined selecting elements to actuate the selected recording members, and selector switches operable individually by the setting up means and by the multiplying means for controlling the operation of the selecting elements.

12. In combination, a multiplying mechanism, a perforating mechanism comprising a plurality of perforating members, means for actuating the perforating members, and means for determining the perforating members to be actuated including selecting members each operable to select any one of a plurality of perforating members for actuation, and control means for controlling the operation of the selecting members, said control means including a key operated mechanism and selector switches controlled by the multiplying mechanism and other selector switches controlled by the keys of the key operated mechanism, said selector switches comprising a plurality of fixed contact members, and contact brushes associated with said contact members.

13. A machine of the class described comprising in combination a multiplying device and a punching device controlled thereby and having provisions for punching a product formed by the multiplying machine upon a card record, said punching machine also including provision for punching factors entering into the multiplying computation upon the card record receiving the product and means intermediate said multiplying machine and the punching machine for selectively controlling the punching machine to cause the latter to punch the product at the desired selective columnar positions upon the record in desired variable relation with the factor data upon the record.

14. A multiplying machine provided with a card punching device for providing card records with perforated data representative of products computed by the multiplying machine, said products being placed upon each card record in proximity to perforated factor data upon the card

record which corresponds to the factors of the computation, comprising a product receiving means in the multiplying machine and means controlled by said means for transferring back to the card record upon which perforated factor data of the computation appears the complete product which is computed by the multiplying machine and set up on the final product receiving means, said last mentioned means including provisions for correlating the location of the product perforations with the factor perforations which correspond to said product.

15. In a machine of the class described, including a multiplying machine having an accumulator which ultimately receives the final product computed by the machine from two entered factors, a punching device through which pass records which emerge with factor designating perforations thereon and which records are punched by the operation of the punching device with product designating perforations in proximity to the factor designating perforations of the computation, and means for controlling actuation of the punching device from the aforesaid accumulator of the multiplying machine and for correlating the location of the product perforations in proximity with the factor designating punchings whereby the product is perforated upon the record upon which the factors entering into the computation are perforated.

16. A calculating machine including in combination with multiplying devices having product receiving means, of means controlled by the product receiving means of the multiplying devices for recording a product upon a record, said recording means comprising a plurality of recording selector elements which are greater in number than the number of columns of the product to be recorded, a plurality of means less in number than the number of the recording selectors and adjustable for selecting which of the various recording selectors are to be effective to record the product whereby the product may be recorded on optionally different fields of a relatively stationary record.

17. A record making accounting machine with a record punching means, multiplying devices for multiplying factors including a final product receiving means, means controlled by the final products receiving means for controlling the punching means, means for causing the final products receiving means to accumulate successively computed separate products, and means adjustable at the will of the operator to permit the omitting of the punching out of any desired product or products amount and to permit the punching of a desired product amount.

18. In an electrical multiplying machine comprising a multiplicand storing device, a multiplier storing device, a product register, means for performing the process of multiplication by forming subproducts of all digits of one factor by each digit of the other factor and accumulating the subproducts in the product register, means under control of said register for recording the accumulation of the product and manipulative electrical means interconnecting said register and said recording means for selectively recording any of the digits of the product in a subsequent recording operation.

19. In a machine of the class described, including factor entry means and a multiplying mechanism having an accumulator which ultimately receives the final product computed by the multiplying mechanism from two entered factors, a

5 punching device through which records are fed and wherein product designating perforations are punched in proximity to the factor designating perforations of the computation, means for controlling actuation of the punching device from the factor entry means, and means for controlling actuation of the punching device from the aforesaid accumulator to punch a multi-denominational product, said last mentioned means including provisions for spacing the product punching upon the record card in any desired relationship to the factor punchings thereon.

10 20. A calculating machine including in combination with multiplying devices having factor storing means and product receiving means, of means controlled by the factor storing means and the product receiving means of the multiplying devices for recording the factors and product respectively upon a record, said recording means comprising a plurality of recording selector elements which are greater in number than the number of columns of the factor and of the product to be recorded, a plurality of means less in number than the number of the recording selectors and adjustable for selecting which of the various recording selectors are to be effective to record the factors and the product whereby the factors and the product may be recorded on optionally different fields of a record.

25 30 21. In a machine of the class described, a plurality of entry receiving and retaining devices, a computing mechanism controlled thereby, a plurality of result indicating devices controlled by the computing mechanism, each of the said devices pertaining to a separate denominational order, a recording device for recording data standing thereon, a plurality of emitters corresponding to said entry receiving and result indicating devices, each adapted to emit a single series of impulses representative of different data to its corresponding entry receiving or result indicating device for selecting for control of the recording device only such impulses as correspond to data standing on the particular element of the entry receiving or product indicating device, and adjustable means for controlling the recording device to determine just which of the received data and result data shall be recorded.

35 40 45 50 55 60 22. In a computing and recording machine, means for simultaneously storing a plurality of factors, means including a product accumulator for effecting a multiplication as determined by the factor storing means, a recording mechanism controlled by said accumulator to record the result of a multiplication on a record card, means for automatically feeding a card through the recording mechanism for each multiplication, and manipulative means interconnecting said accumulator and said recording mechanism to determine the recording of any or all of the digits of the result in any desired area of the record card.

65 70 75 23. In an electrical computing and recording machine, means operable for setting up digits of factors, a multiplying means, an accumulator, means for actuating the multiplying means to effect the completion of circuits through the accumulator as controlled by the operated setting up means to obtain an indication of the result of a multiplication, and a recording means electrically connected to the accumulator and to the setting up means for recording the factors and the result in any desired predetermined area on a record sheet.

24. In a perforating apparatus, a plurality of perforating members, selecting means for con-

trolling the actuation thereof, means for controlling the operation of said selecting means, a multiplying mechanism, means operable to store information for subsequently controlling the operation of the means which control the operation 5 of the selecting means and for controlling the operation of the multiplying mechanism, and means

for connecting the multiplying mechanism and the information storing means to any of the means for controlling the operation of the selecting means.
